UNITED STATES PATENT OFFICE.

JAMES SPEAR, OF WALLINGFORD, PENNSYLVANIA.

DESIGN FOR A STOVE.

SPECIFICATION forming part of Design No. 32,645, dated May 8, 1900.

Application filed March 30, 1900. Serial No. 10,855. Term of patent 14 years.

To all whom it may concern:

Be it known that I, JAMES SPEAR, a citizen of the United States, and a resident of Wallingford, county of Delaware, State of Pennsylvania, have invented and produced a new and original Design for Stoves, of which the following is a specification.

In the accompanying drawing, forming a part of this specification, a perspective view of a stove of my new design is shown.

The leading or material feature of my design consists in the shape or configuration of the stove as disclosed in the drawing.

Referring to the drawing, *a* is the top portion, and *b* the bottom portion, of the stove.

Both of these portions have substantially the forms of truncated cones, the smaller ends of which are joined at the middle of the stove and the bases of which form, respectively, its top *c* and bottom *d*. 20

Having thus described my invention, I claim as new and desire to secure by Letters Patent—

The design for a stove as herein shown and described.

JAMES SPEAR.
